UNITED STATES PATENT OFFICE.

JOSEPH J. BENNETT, OF PITTSFIELD, MASSACHUSETTS, ASSIGNOR OF ONE-HALF TO LOANDO B. ESTES, OF NORTH ADAMS, MASSACHUSETTS.

MOUNTING FOR TROLLEY-HEADS.

No. 905,784.

Specification of Letters Patent.

Patented Dec. 1, 1908.

Application filed August 6, 1906. Serial No. 329,320.

To all whom it may concern:

Be it known that I, JOSEPH J. BENNETT, a citizen of the United States of America, residing at Pittsfield, in the county of Berkshire and State of Massachusetts, have invented new and useful Improvements in Mountings for Trolley-Heads, of which the following is a specification.

This invention relates to improvements in mountings for trolley-wheels, and its particular object is to provide a structure that will permit the trolley-wheel to readily adapt itself to any irregularities in the trolley-wire, especially going around sharp curves or corners, (as when the car passes around the corner from one street to another,) that are generally at right angles to each other; the mounting of the wheel being so arranged that the same freely follows the curvature of the trolley-wire without producing undue friction or grinding between the flanges of the wheel and wire, thus lessening to a great extent the danger of breakage of either the wire (or its fastening means) or trolley-pole.

In the drawings forming part of this application,—Figure 1 is a plan view of the trolley-wire from above and showing the wheel in various positions of adjustment in dotted lines. Fig. 2 is a side elevation of my improvement, and a portion of the upper end of the trolley-pole which carries the wheel mountings. Fig. 3 is a sectional plan view on the line 3—3 of Fig. 2 looking in the direction of the arrow.

Referring to the drawings in detail, *a* designates a portion of the ordinary overhead trolley-wire that is engaged on the under side thereof by the trolley-wheel *b* that is adapted for rotation on the pin *c*. This pin is mounted in the upright ears *d* and secured against loss and rotation by means of the enlargements *e* thereon, and cotter-pins *f*, in the usual manner.

g designates a base-piece having a depending portion *h* and an arm *i* that is cast in one piece and mounted in the upper end of the trolley-pole *j*, being secured therein by means of the pin *k*. The base-piece *g* is provided with two angular sector-shaped recessed portions *m* that are adapted to receive correspondingly shaped lug portions *n* that are cast integral with the rotatable head *o*. The rotatable head *o*, ears *d*, and lugs *n* are cast in one piece.

It will be noticed from the view shown in Fig. 3 that the length of the arc of the lug-
portions *n* is less than the length of the arc
of the recesses *m* of the base-piece *g* in order
to permit a sufficient amount of movement
of the rotatable head-piece *o* on the base-
piece *g* in going around any curve of the
trolley-wire that may occur in practice, or in
other words to allow the trolley-wheel *b* which
is carried by the ear-pieces *d* free rotative
movement relative to the base-piece *g*.

The rotatable head-piece *o* is secured to
the base-piece *g* by means of a threaded stud
p that is passed through a hole *o'* in the piece
o. This stud is cast with the base-piece *g*
and afterwards threaded. It is provided
with a shoulder *q* that extends slightly
above the piece *o* and against which the
securing nut *r* is firmly secured in order to af-
ford a slight play between the pieces *g* and *o*,
and to prevent the drawing together of these
two pieces in a solid manner. The nut *r* is
retained against loss by means of the cotter-
pins *s*.

By means of this construction it is easily
seen that when a car passes around a curve
the trolley-wheel *b* is permitted to follow the
irregularities of the trolley-wire *a* without
undue friction or grinding of the flanges of
the wheel on the wire, as readily understood,
and avoid any danger of breaking either the
wire or any of the mountings of the trolley-
wheel. This movement of the wheel is ac-
complished by the rotatable head-turning
piece *o* on the stud *p*, and the arch-shaped
lugs *n* traveling in the larger arch-shaped, re-
cesses *m* of the base-piece *g*. Enough space
is left between the sides of the parts of the
lugs *n* and the sides of the recesses *m* to per-
mit the wheel *b* to pass around any curve of
the wire that would be found in practice.

The dotted line positions of the trolley-
wheel indicated in Fig. 1 clearly illustrate
the various positions that the wheel may as-
sume as it follows the curves of the trolley-
wire.

What I claim, is:—

A mounting for trolley-wheels having in
combination a base-piece *g*, a depending por-
tion *h*, an arm *i* integral with the base-piece
and adapted to be mounted in the upper end 105
of the trolley-pole, the base-piece being pro-
vided with two angular sector-shaped re-
cessed portions *m*, a rotatable head *o*, sector-

shaped lug portions n integral therewith and engaging the angular-shaped recessed portions m of the base-piece, the length of the arc of the lugs being less than the length of
5 the arc of the recessed portion of the base-piece, a threaded stud p integral with the base-piece g and passed through a hole o^1 in

the rotatable head o whereby limited rotative movement between the base g and the head-piece o is effected.

JOSEPH J. BENNETT.
